United States Patent Office

Des. 182,659
Patented Apr. 29, 1958

182,659

BROOM

Ralph Stewart Hall, Compton, Calif.

Application February 11, 1957, Serial No. 44,820

Term of patent 14 years

(Cl. D9—2)

FIG. 4

Figure 1 is a front elevational view of a broom embodying my new design;

Figure 2 is a fragmentary perspective view on an enlarged scale of the broom shown in Figure 1;

Figure 3 is a fragmentary end elevational view of Figure 2; and

Figure 4 is a top plan view thereof.

I claim:

The ornamental design for a broom, substantially as shown.
